UNITED STATES PATENT OFFICE.

WILLIAM R. FOX, OF GRAND RAPIDS, MICHIGAN.

TYPE-WRITER.

1,254,321.

Specification of Letters Patent. Patented Jan. 22, 1918.

Original application filed November 6, 1909, Serial No. 526,552. Divided and this application filed January 19, 1914. Serial No. 813,034.

To all whom it may concern:

Be it known that I, WILLIAM R. Fox, a citizen of the United States, residing at Grand Rapids, in the county of Kent and State of Michigan, have invented certain new and useful Improvements in Type-Writers, of which the following is a specification.

This invention relates to improvements in typewriters, and particularly to an improved structure for perforating a stencil card. This application is a division of my pending application, Serial No. 526,552, filed November 6, 1909.

The object of this invention is, to provide an improved perforating device for perforating stencil cards in which needle point type can be effectively used because the same are protected from injury.

Further objects, and objects relating to details and economies of structure and operation will definitely appear from the detailed description to follow.

I accomplish the objects of my invention by the devices and means described in the following specification. The invention is clearly defined and pointed out in the claims.

A structure constituting a preferred embodiment of my invention is clearly illustrated in the accompanying drawing forming a part of this specification, in which:

Figure I is a view partly in section and partly in elevation, showing my improved type bar in its proper relation to the platen. Fig. II is an enlarged detail perspective view of one of the type.

Fig. III is transverse sectional view on a line corresponding to line 3—3 of Fig. I, through one of the type showing the manner in which the type head is constructed.

In the drawing, the sectional view is taken looking in the direction of the little arrows at the ends of the section line, and similar numerals of reference refer to similar parts throughout the several views.

Considering the numbered parts of the drawing, I have shown my invention in connection with a stencil card holder of the type shown in my pending application above referred to. 1 is a base carrying the card holder and provided with a pair of stands 3, 3 to the upper ends of which the arms 4, 4 are pivoted at 2. 5 is the card holder which is pivoted at 6 to the ends 55 of the arms 4, 4. This card holder is pro-

vided with rearwardly projecting arms 13, 13 at each side, which are connected by a cross bar 14. The ends of the platen are provided with suitable spur gears 8 meshing with racks on the card holder. The platen 9 has a canvas covering 9' into which the needle point type penetrate when perforating the stencil card 15. The card holder has a ledge 11 at the bottom with an upwardly projecting flange 12 at the rear for effectively engaging the card. Springs 10 are connected to the card holder at each side and extend rearwardly therefrom and connect with downwardly projecting fingers on the arm 4.

The type bar 16 is, in the particular structure here illustrated, arranged below the platen after the manner of the front-strike typewriter. This bar carries a type 17 provided with pin points 18 for perforating the stencil card. On the back of this head is a felt pad 20 which is retained in place by a sheet metal clip 19, as clearly appears from an inspection of Fig. III. This metal clip 19 forms in effect a socket 70 in which the felt pad 20 is seated.

It will thus be clear that, if accidentally, two type bars are struck forward at the same time, the second one moved to position will not be injured because the pin points 85 of that type will penetrate the soft felt pad 20 on the back of the next one and no harm will be done further than to make it necessary to separate the type and let them drop back to their initial position. In this manner I 90 avoid injuring the pin points of the type and render them effective for perforating the card. I have not illustrated the details for operating the type bar because they are in common use, and any effective and satisfactory means can be made use of. Furthermore, I have not illustrated the means for actuating the platen because they are well known and my invention has nothing to do with the same.

I am aware that the particular embodiment which I have here shown can be varied considerably without departing from the spirit of my invention and, therefore, I do not wish to be restricted to the same. I 105 have found, however, that this form is to be preferred, and, therefore, I desire to claim the same specifically as well as broadly as indicated by the appended claims.

Having thus described my invention, what 110

I claim as new and desire to secure by Letters Patent, is:

1. In a typewriter, a series of pin-pointed type, metal clips embracing said type and forming, with the rear thereof, sockets, and pads seated in said sockets on the back of said type.
2. A metallic type bar carrying a metallic type and having a socket in which is seated a buffer of material softer than the type and against which a part of another type bar is adapted to strike.
3. A type bar having a socket in the rear of the impact face of the type, and a pad seated in said socket.

4. A type bar having a rearwardly opening socket, and a pad seated and secured in said socket and extending rearwardly from the type bar.

5. A type bar having a needle faced type and a socket in the rear of the type, and a pad seated and secured in said socket and extending rearwardly from the type bar.

In witness whereof, I have hereunto set my hand and seal in the presence of two witnesses.

WILLIAM R. FOX. [L. S.]
